UNITED STATES PATENT OFFICE.

ALEXANDER HORVATH, OF FARRELL, PENNSYLVANIA.

WALDEMAR BREAST WATCH.

Application filed December 13, 1920. Serial No. 430,324.

To all whom it may concern:

Be it known that I, ALEXANDER HORVATH, a citizen of the United States, and resident of Farrell, in the county of Mercer and 5 State of Pennsylvania, have invented a new and useful Improvement in Waldemar Breast Watches; and I do hereby declare the following to be a full, clear, and exact description thereof.

10 My invention relates to watches, and it has for its object to provide novel means for wearing a watch, so that the watch shall be in convenient position to be consulted and the whole device shall present the appearance 15 of the well known Waldemar watch chain or ribbon.

It is very common to carry a watch in the breast pocket, attached to the end of a chain which extends across the waistcoat of the 20 wearer, the other end of the chain being attached to a suitable object carried in the opposite pocket. Such a chain is known as a "Waldemar chain." The chain is often replaced by a ribbon and in this case it is 25 customary to provide the ribbon with a suitably engraved buckled or other ornament that is carried at the middle of the ribbon.

According to my present invention, I attach the watch to a plate or case having the 30 general appearance of the buckle or ornament mentioned above, and I provide this plate or case with ribbons, chains or the like, extending to the two breast pockets of the wearer, the ends of the ribbons being 35 held in place by means of suitable clasps which slide over the upper edges of the wearer's breast pockets. The watch thus presents the appearance of an ordinary Waldemar breast chain or ribbon, but the 40 watch itself is in a convenient position to be consulted by merely tilting the plate or case to bring the face of the watch into view.

In the accompanying drawing, Fig. 1 is a front view of one form of my device 45 including the watch, ribbons and clasps; Fig. 2 is a top view of the same device; Fig. 3 is a side view of one of the clasps; Fig. 4 is a front view of another form of my device; Fig. 5 is a rear view of the watch shown in 50 Fig. 4; Fig. 6 is a top view of the watch shown in Figs. 4 and 5, and Fig. 7 is a rear perspective view of one form of my invention, showing the watch-exposing opening.

As shown in Figs. 1 and 2, the watch 55 movement is contained in a case 2 which, as shown, has one flat side 3 which receives the

bezel 4 of the watch and has a curved outer side 5 which may be engraved with a suitable monogram, name, emblem or the like, or ornamented with jewels or otherwise, as 60 may be desired. The top of the case 2 may be provided with an opening to receive the winding stem of the watch, in which case the crown 6 projects slightly above the case. The crown may be concealed behind the case 65 if desired, as by pivoting the watch case to the buckle instead of enclosing it completely as shown.

At the ends of the case 2 are flat rings 7 to which are attached the ends of ribbons 8, to 70 the outer ends of which are secured clasps 9 having flat rings 10 corresponding to the rings 7 for attaching the ribbons. The clasps 9, as shown in Fig. 3, consist of front and rear fingers 9^a pivoted together at 11 75 and provided with a suitable spring 12. The case 2 may contain the watch movement, like an ordinary watch case or it may be a container, in addition to the usual watch case, for receiving a watch with its case. 80

The form of device shown in Figs. 4 and 6 differs from that described above in that the watch 14, instead of being enclosed within the case 2, is attached to the rear side of a plate 15, the front of which may be engraved or ornamented in any desired manner. As shown, the watch 14 is held in a ring 16 soldered or otherwise secured to the back of the flat plate 15. This plate is also provided with flat rings 17 for attaching the 90 ribbons 18, the rings 17 being attached to the back of the plate some distance from its ends. The ribbon may, if desired, be provided with adjusting clips 20 and are secured to clasps 21 similar to the clasps 9 described 95 above.

Fig. 7 shows the rear surface of the device of Figs. 1 and 2 modified by attaching the ribbons to the flat surface 3 by means of links 17 in the manner shown in Figs. 5 100 and 6.

In use, the clasps 9 are secured to the top edges of the wearer's breast pockets with the engraved or ornamented front of the watch case or plate exposed to view and the face 105 of the watch concealed. The watch may then be consulted by tilting it slightly forward. At other times the entire device presents an appearance similar to that of an ordinary Waldemar watch chain or ribbon. 110

Instead of ordinary ribbons; chains or elastic strips may be employed for connect-

ing the watch and the clasps. Numerous other changes may be made in the form and arrangement of parts without departing from my invention and I therefore desire that my invention be understood to include all such changes or adaptations as fall within the scope of the appended claims.

I am aware that watches have been attached to the clothing by means of pins on which the watch is pivoted, and also by means of chains in the nature of bracelet chains having pins in their end links intended to be forced into the clothing. Also, I am aware that various pockets, holders and the like have been provided for holding watches in a convenient position to be consulted by tilting the pocket or holder. I do not claim such arrangements as these, but I do claim as my invention:

1. As a new article of jewelry, a watch-container having a flat side provided with an opening to expose the face of the watch and also having a curved side opposite to said flat side, and flexible members connected to said container and provided at their ends with clasps adapted to slip over the upper edges of the wearer's breast pockets and to thereby suspend the said watch container between the said pockets.

2. As a new article of jewelry, a watch

container having a flat side adapted to rest against the wearer's breast, the said flat side being provided with an opening to expose the face of the watch, and ribbons connected to the flat side of said container and provided at their ends with clasps adapted to slip over the upper edges of the wearer's breast pockets and to thereby suspend the said watch container between the said pockets.

3. As a new article of jewelry, a watch container having a flat side adapted to rest against the wearer's breast and a curved side opposite to said flat side, the said flat side being provided with an opening to expose the face of the watch, links carried by the flat side of said case near opposite edges thereof, and ribbons connected to said links and provided at their outer ends with clasps adapted to slip over the upper edges of the wearer's breast pockets and to thereby suspend the said container between the said pockets.

In testimony whereof, I the said ALEXANDER HORVATH have hereunto set my hand.

ALEXANDER HORVATH.
